COMBINED HAND AND FOOT MOTOR FOR CHURNS.

APPLICATION FILED SEPT. 17, 1907.

2 SHEETS—SHEET 2.

UNITED STATES PATENT OFFICE.

DANIEL PUMP MALONE, OF ROCKWOOD, ALABAMA.

COMBINED HAND AND FOOT MOTOR FOR CHURNS.

No. 880,229.

Specification of Letters Patent.

Patented Feb. 25, 1908.

Application filed September 17, 1907. Serial No. 393,369.

To all whom it may concern:

Be it known that I, DANIEL PUMP MALONE, a citizen of the United States, residing at Rockwood, in the county of Franklin and 5 State of Alabama, have invented certain new and useful Improvements in Combined Hand and Foot Motors for Churns; and I do hereby declare the following to be a full, clear, and exact description of the invention, such as 10 will enable others skilled in the art to which it appertains to make and use the same.

My invention relates to combined hand and foot motors for churns, and the object of my invention is to provide such a motor that 15 will be simple in construction, cheap to manufacture, certain in operation, which shall be easily taken apart and cleaned, and which shall be equally as well adapted to be operated by either the hand or the foot.

20 To these ends my invention consists in the combination of parts more fully hereinafter disclosed and particularly pointed out in the claims.

Referring to the accompanying drawings 25 forming a part of this specification:—Figure 1 represents a side elevational view of my motor applied to a churn. Fig. 2, an end elevational view. Fig. 3, a sectional view of the complete device. Fig. 4, a detached 30 tail view of the head of the dasher rod and its connections with the motor. Fig. 5 a perspective view of the dasher, its rod, and attached cam plate, and Fig. 6, a perspective view of the eccentric which drives the dasher.

35 Like letters refer to the same parts in all the views.

A represents a suitable base, B a standard rising therefrom, and C, D and E three horizontal shafts supported by said standard.

40 F represents an enlarged bearing or head integrally connected with said standard B by the short neck Q, or it may be made separate from said standard B and connected therewith by a separate piece. Suitably pivoted 45 upon the shaft C is the foot lever G, supported at its outer end by a short standard B², and suitably pivoted upon the shaft D I provide the wheel M provided with a groove N. A link H connects the foot lever G with 50 the pin J passing through said wheel M, and provided with a nut K on one side and a washer L on the other. The pin J is sufficiently long and of a sufficient size to serve as a handle to operate the wheel M by hand if the 55 link H and foot lever G should be disconnected from the machine.

Suitably attached to the shaft E is the wheel P likewise provided with a groove, and the cord or other band connection O joins the said wheels M and P, and serves to transmit power from the one to the other. The shaft E is provided at its end opposite from that on which the wheel P is fixed, with a disk R, provided with a pin S eccentrically placed thereon, as clearly shown in Fig. 6. 60 This disk R I have shown as being formed integral with the shaft E, but, of course, I may form it separate therefrom and suitably attach it to said shaft.

The eccentric pin S is provided with a suitable roller T. The head F is provided with a slotted, or cut away, face, best shown in Fig. 4, over which slides the cam grooved plate A', rigidly attached to the dasher rod V, and in whose cam groove B' the eccentric pin S, 70 with its roller T, slides. The head or bearing F is also provided at its top and bottom with suitable guide grooves for the dasher rod V to work in, as best shown in Figs. 3 and 4, and it is also provided with undercut grooves 80 C' for the cover W to slide in. The cover W is provided with a suitable groove at its center to accommodate the dasher rod V, as indicated by the dotted lines in Fig. 3. The cam grooved plate A' is provided with vertical bearing edges E', which take against and are guided by the vertical edges D' of the outer walls of the grooves C', as best shown in Fig. 4. At the lower end of the dasher rod V, I provide a suitable dasher F'. A 85 churn G', provided with a suitable cover H' is received in a suitable recessed seat J' formed in the base A, as shown. I preferably provide my churn with a pair of cam lugs K', as shown in Fig. 1, which take under 90 a pair of suitable fastenings lug L', as best shown in Figs. 1 and 2, rigidly attached to the seat J'. The effect of the lugs L', K', is to firmly lock and hold the churn in place, while when it is desired to remove the churn, 100 or unlock the same, it is only necessary to turn the churn bodily around until the lugs K' disengage the lugs L'.

The operation of my power transmitting device is as follows:—Upon power being applied to the foot lever G, the same is transmitted through the link H to the pin J, the wheel M, band O, wheel P, shaft E, disk R, eccentric pin S, cam plate A', dasher rod V, and dasher F', causing the latter through the 105 cam B' to be reciprocated up and down in the churn G'.

Whenever it is desired to disassemble the parts for cleaning, the cover W is removed from the bearing F, the dasher disengaged from the eccentric S and taken from the churn. The shaft E may then be taken out of the connection Q, which frees the wheel P. The nut K is readily removed, and the link H and lever G as readily disassembled. When this is done, the wheel M, with its shaft D, 10 can be easily removed from the standards B, and the whole machine is thus taken apart, and ready for scalding and cleansing. Of course it can be just as readily assembled and started into operation again.

15 By removing the nut K and the link H, as above described, the pin J serves as a handle to operate the wheel M and the churn may be driven by hand.

Having now described my invention, what 20 I claim, is:—

1. In a combined hand and foot motor for churning, the combination of a base, a standard rising therefrom, three horizontal shafts carried by said standard, a foot lever carried 25 by one of said shafts, and a grooved wheel carried by each of the others, a link connecting said foot lever and one of said wheels, and a band joining the said wheels, an eccentric carried by one of said shafts, a dasher rod carrying a cam plate in which said eccentric operates, said cam plate provided with the 30 straight guide edges E', bearings against which said edges slide, and a dasher attached to said rod, substantially as described.

35 2. In a combined hand and foot motor for churning, the combination of a base, two standards rising therefrom, three horizontal shafts carried by one of said standards, a foot lever carried by one of said shafts and supported 40 by both of said standards, and a grooved wheel carried by each of the others, a link connecting said foot lever and one of said wheels, and a band joining the said wheels, a disk provided with an eccentric having a 45 roller carried by one of said shafts, a dasher rod carrying a cam plate having a heart shaped cam in which said eccentric operates, said cam plate provided with the straight guide edges E', bearings against which said 50 edges slide, and a dasher attached to said rod, substantially as described.

3. The combination of a churn and a combined hand and foot motor provided with a base, two standards rising therefrom, a shaft

passing through said standards, a foot lever 55 carried by said shaft, a second shaft carried by one of said standards, a wheel on said second shaft and provided with the pin J, said pin being of such dimensions as to be capable of being used as a handle, a link connecting said lever and pin, a washer and a nut on said pin, a third shaft carried by one of said standards, a second wheel fixed to said third shaft, a band connecting said wheels, a bearing or head F carried by one of said standards through which said third shaft passes, a disk carrying an eccentric pin and roller carried by said third shaft and working in said head F, a dasher rod provided with a plate having a heart shaped cam therein, 70 receiving said pin and roller, said plate having straight guide edges E', and said head F having straight guide edges D' against which said edges E' slide, said head F also having undercut grooves C', a cover W working in 75 said grooves, and a dasher F' on said dasher rod, substantially as described.

4. The combination of the base A, provided with the seat J' and lugs K', the standards B and B', the shaft C, journaled in said 80 standards, the foot lever G, carried by said shaft, the shaft D carried by said standard B, the wheel M carried by said shaft and provided with the groove N and pin J, the washer L, and nut K on said pin, the link H joining 85 said lever G and pin J, the shaft E, the wheel P carried by one end of the same, the band O connecting said wheels M and P, the head F, the connection Q between the same and said standard, the said head provided with the undercut grooves C', having the straight edges D', the disk R, eccentric S and roller T carried by said shaft E, said disk fitting into a recess with which said head F is provided, the dasher rod V provided with the plate A' 90 having the straight edges E' adapted to slide on the said edges D', and the heart shaped cam B' in which said pin and roller is adapted to operate, a dasher F' on said rod, a churn G', and lugs L' on said churn, adapted 95 to engage the lugs K' on said seat, substantially as described.

In testimony whereof, I affix my signature, in presence of two witnesses.

DANIEL PUMP MALONE.
